UNITED STATES PATENT OFFICE

FRANK S. FENTON, OF CINCINNATI, OHIO, ASSIGNOR TO FENTON'S SANDWICH, INC., OF CINCINNATI, OHIO, A CORPORATION OF OHIO

DESIGN FOR A RESTAURANT BUILDING

Application filed April 1, 1930. Serial No. 35,095. Term of patent 3½ years.

To all whom it may concern:

Be it known that I, FRANK S. FENTON, a citizen of the United States of America, and a resident of Cincinnati, in the county of Hamilton and State of Ohio, have invented a new, original, and ornamental Design for a Restaurant Building, of which the following is a specification, reference being made to the accompanying drawing, forming a part thereof.

The figure is a perspective view of a restaurant building, showing my new design. The opposite sides are substantially the same as those now shown.

I claim:

The ornamental design for a restaurant building as shown and described.

FRANK S. FENTON.
